UNITED STATES PATENT OFFICE

ADOLF LÖFFLER, OF UNION COURSE, NEW YORK.

MECHANICAL RAILWAY-SWITCH-OPERATING MEANS.

1,134,627.

Specification of Letters Patent.

Patented Apr. 6, 1915.

Application filed January 11, 1915. Serial No. 1,576.

To all whom it may concern:

Be it known that I, ADOLF LÖFFLER, a subject of the Emperor of Germany, residing at Union Course, in the county of Queens and State of New York, have invented new and useful Improvements in Mechanical Railway-Switch-Operating Means, of which the following is a specification.

My invention relates to mechanical railway switch operating means and has as its principal object the provision of simple but reliable and efficient mechanism whereby the position of a switch may be controlled by the motorman or engineer on a car.

A further object of my invention resides in the particular arrangement and combination of parts hereinafter described.

In the accompanying drawings:—Figure 1 is a sectional view taken on a plane parallel to the tracks and showing the operating members carried by the car as well as the major portion of the apparatus which is grounded in a channel transverse to the track. Fig. 2 is a detail sectional view showing that part of the mechanism carried by the car which is broken off from the top of Fig. 1. Fig. 3 is a section taken on the line A—A of Fig. 2. Fig. 4 is an elevational view of a car fitted for use in connection with my apparatus. Fig. 5 is a sectional view on the line c—c of Fig. 6. Fig. 6 is a plan view of a track and a switch point showing my invention applied thereto. Fig. 7 is a plan view of a portion of the car having my operating pedals applied thereto, the body of the car being broken away for purposes of illustration.

In the separate views the same part is designated by the same reference character. Referring more particularly to the drawings, 1 is a car of any improved type which is shown in Fig. 4, as fitted with two pedals 2—2 for operating the portion of the apparatus mounted in connection with the track. The pedal mechanism is illustrated in Fig. 2, the upper part of Fig. 1 and Fig. 3.

3 is the floor of the car through which extends a hollow cylinder 4 which is braced by a bracket 5^a fastened to the under side of the floor 3. Through the cylinder 4 extends a rod 5 which carries a pedal 6 at its upper end. A spring 7 is provided within the cylinder 4 which pushes against a collar 8 of the rod 5 so as to normally maintain the pedal in the position shown in Fig. 2. In Fig. 1 the rod 5 is shown in the position as-

sumed when the pedal 6 is depressed. The lower end of the cylinder 4 is contracted as shown at 9 in Fig. 1 so as to afford a guide for the rod 5 which projects therethrough.

I provide a chamber 10 which extends transversely of the track and in the chamber 10 is journaled a shaft 11 as shown at 12—12 in Fig. 5. I also provide a slot 13 which is in alignment with the rod 5 and into which it is adapted to extend when the pedals are depressed.

Rigidly mounted near the center of the shaft 11 is a four pointed star wheel 14, the arms or points of which project up into the slot 13 so as to lie in the path of the rod 5. It will be seen from the drawing that as the rod 5 is carried forward by the car, the wheel 14 will be turned about one-eighth of a revolution. Since there are four arms or points to the wheel 14 it is necessary that it be turned one-fourth of a revolution in order that the succeeding arm or point may project into the slot 13. To accomplish this I provide a second wheel 15, somewhat smaller than the first, which is also provided with four arms or points, the surface of the wheel intermediate the points being curved preferably on arcs or circles, and the points being set intermediate the points of the wheel 14. I also provide two levers 16—16 which are pivoted in the bottom of the chamber 10, the upper ends of which are approximately level with the shaft 11. Pivoted in the upper ends of the levers 16 are two rollers 17—17 one in each arm, which lie on opposite sides of the shaft 11.

Intermediate the levers 16 is a spring 18 which draws the levers together. In consequence of the action of the spring the rollers 17 seat themselves in the circular recesses intermediate the arms or points of the wheel 15. Consequently when the wheel 14 and shaft 11 are turned by the operation of one of the rods 5 the rollers 17 are spread apart by the points of the wheel 15 and as soon as the spreading points have passed the center of the rollers, that is, when the wheel 14 has been turned a very little more than one-eighth of a revolution, the spring 18 will draw the rollers together again thus forcing wheel 15 around and completing a quarter turn of the wheels and shaft.

At one end of the shaft 11 is a cam 19 which is rigid with the shaft and which is provided with a cam surface forming alternate projections and recesses, the projec-

tions being approximately 180 degrees apart, and the elements of the surface being approximately at right angles to the axis of the shaft 11. Engaging the surface of the cam 19 is a pin 20 which is fixed to a switch point 21 pivotally mounted in the usual manner in connection with the track 22. I provide also a second cam member 23 which is splined to the shaft 11 by the feather such as 24, a spring 25 being provided to throw the member 23 against the pin 20. It will be seen from the drawings that members 19 and 23 have complementary cam surfaces, the hollows in one member being opposite the projections in the other so that a cam slot or groove 26 is formed into which pin 20 projects. It will be obvious also that when the shaft 11 is turned 90 degrees in the manner previously described that the pin 20 will be shifted in a direction parallel to the axis of the shaft 11, while the switch point 21 will be turned so that the car may be guided in either direction as desired.

It will be obvious that the motorman or engineer does not need to depress the pedal 2 unless he desires, and consequently when approaching the switch if he sees that it is in the proper position he need take no action, but if the switch is set wrong he merely presses the pedal as he arrives over the slot 18 whereupon the switch point will be shifted in the manner just described.

It will be understood that while I have shown and described the preferred form of

my invention, that I do not wish to be limited to the specific mechanical features illustrated.

Having thus described my invention, what I claim is:—

The combination with a switch point, of a pin connected thereto, means forming a chamber beneath said point into which said pin projects, a shaft journaled in said chamber, cam means carried by said shaft adapted to shift said pin to move said point from one of its normal positions to the other at each operation of the shaft, a star wheel fastened to said shaft and projecting upwardly therefrom toward the surface, a normally raised depressible rod carried by the car for operating said star wheel, said star wheel having four points or arms, a second star wheel carried by said shaft also having four points or arms but having its arms set intermediate those of the first mentioned star wheel, a pair of pivoted levers set on opposite sides of said second mentioned star wheel, rollers pivoted in the ends of said levers, and spring means for forcing said rollers against the face of said second mentioned star wheel.

In testimony whereof I affix my signature in the presence of two witnesses.

ADOLF LÖFFLER.
